UNITED STATES PATENT OFFICE.

JOSEPH P. COWAN, OF PITTSBURGH, PENNSYLVANIA.

WATER-CLOSET.

1,077,221.

Specification of Letters Patent.

Patented Oct. 28, 1913.

Application filed November 28, 1910. Serial No. 594,428.

To all whom it may concern:

Be it known that I, JOSEPH P. COWAN, a citizen of the United States, residing at Pittsburgh, in the county of Allegheny and State of Pennsylvania, have invented a new and useful Improvement in Water-Closets, of which improvement the following is a specification.

My invention relates to water closets, and 10 more particularly to the parts connecting the seat with the bowl.

Closet bowls are ordinarily made in several sizes, and owing to variations in location of the bolt holes therein for securing the seat connections thereto, it has been necessary to have seats and connections to suit each size, said openings varying transversely, between the same, from about 5 $\frac{3}{8}$ to 5 $\frac{1}{4}$ inches, and from the front edge of the 20 bowl to said openings from 16 to 17 inches.

My invention has for its object to provide connecting means adapted to suit several sized closet bowls and to bring about proper positioning of the seat with respect to the 25 bowl, which has heretofore been found practically impossible particularly where it be desired to employ one particular form of seat to the different makes of bowls, such 30 improper positioning being due to variation in the distance at which the openings in the rear portion of the bowls, to receive the bolts of the seat connection, are located with respect to the bowl front, as well as a variation in distance between said openings, both 35 of which variations tend to cause the seat to either project too much forward, too much rearward, or laterally, and to cause the seat to assume a position out of alinement with respect to the bowl, thus causing inconvenience 40 in applying the seat as well as affecting its appearance.

My invention has for a further object to provide means to limit the distance which the seat may be elevated and thrown back, 45 it being found in some instances this limiting of the seat movement is desirable, particularly where the lid is dispensed with and the plumbing is exposed at the rear of the seat and liable to be damaged by the 50 seat striking the same.

With the above objects in view, the invention comprises a hinge connection provided with means to connect same to the bowl, the reversal of which means will permit of longitudinal adjustment of the seat 55 with respect to the bowl; means to vary

both the longitudinal and lateral position of the seat with respect to the bowl, and means to limit the distance at which the seat may be raised and thrown back, or not, as may be desired, all of which will be hereinafter more fully described in this specification and shown in the accompanying drawings, forming a part hereof, in which drawings:

Figure 1 is a side elevation of a portion of a closet bowl and seat embodying my improvement, said view being partly sectional and the seat shown as elevated to the point limited by the connections. Fig. 2 is a front view of the seat and connection, 70 showing the seat elevated and means for limiting the seat elevation. Fig. 3 is a similar view showing the connections as applied so as to not limit the seat elevation. Fig. 4 is a plan view of the hinge members, 75 disconnected. Fig. 4^a is an end elevation of the hinge pivotal member. Fig. 5 is an elevation of one of the seat adjusting bolts, in two positions, as employed to secure the connection to the bowl. Fig. 6 is an inverted plan of the adjusting bolt. Fig. 7 is a plan of one of the eccentric washers for adjusting the position of the bolt in the openings of the bowl. Fig. 8 is a side elevation of a portion of the hinge connection 85 showing the bolt adjusted in an opposite direction to that shown in Fig. 1. Fig. 9 is a plan view of a closet bowl.

In said drawings, the reference numeral 1 indicates a closet bowl, of any desired form, provided at its rear with bolt openings 1', through which the bolts of the seat connection pass, said openings being provided with a concave recess at each end 1^a.

2 and 2' indicate two side sections of a 95 sanitary form of seat hingedly connected to the bowl at the rear thereof, by my improved connection, and secured to one another at their forward ends by a transversely disposed segmental shaped member 100 3.

The structural combination and parts here shown comprise an integral hinge pivotal member transversely disposed with respect to the seat and forming a connection for the 105 rear of the divided parts thereof, said pivotal member having its intermediate portion 4 slightly bowed outwardly and its extremities 5 broadened out in right-angular form, in cross section, to correspond with the rear edges and underside of the seat, the broadened portions being provided with 110

openings through which screws 6 pass for securing the member to the seat, said pivotal member having formed thereon a suitable shoulder or abutment 7 from where its 5 pivotal portions 8 project.

To the bowl is secured a pair of hinge posts or standards 9, each comprising an upright portion 9^a having an opening 9^b therethrough within which the portion 8 of the 10 pivotal member is mounted, and an extended base 9' within which is formed an opening 10, preferably of elongated form, the upright portion of each standard being provided with a suitable shoulder or stop 11 15 adapted to be engaged by the abutment or stop 7 on the pivotal member to limit the upward swing of the seat, if desired.

Each standard is connected to the rear of the bowl by means of a suitable bolt 12 and 20 nut 13, said bolt having a laterally disposed or projected head 13', provided with a shouldered portion 14 extending thereabout adapted to fit or engage within the elongated opening 10 in the standard base so as 25 to hold and retain the standard in firm position and preventing the bolt from turning. The bowl openings 1' through which the bolts pass each have loosely seated within the recess portion 1^a formed at each end thereof, an eccentrically formed bolt positioning member or washer 15, of concave form in cross-section, corresponding in form 30 with the recess portion, for the purpose of adjusting the position of the bolt in the opening.

The raising of the seat may be limited to an approximate vertical position by the abutments or stops 7 of the transverse hinge member and the shoulders or stops 11 of the 40 standards 9 coming into engagement with one another, as shown in Figs. 1 and 2, but if it is desired not to limit the raising of the seat the mere transposing of the standards as shown in Fig. 3, so as to bring the abutments 11 outwardly, will permit of the seat 45 being so operated.

By reversing the bolts 12 the seat may be adjusted forwardly or rearwardly in a longitudinal direction, as shown in Figs. 1 and 50 8, as occasion requires for the different sized bowls, to bring the seat in the desired position. By rotatively adjusting the eccentric washers 15 within their recessed seats at the 55 ends of the bolt openings, the position of the bolts passing therethrough may be varied to permit a lesser degree of adjustment of the hinge posts or standards than may be desired by reversing the bolts, or increase or diminish the bolt reversal adjustment, as 60 occasion may require, as shown in Figs. 1 and 8. Furthermore, the rotative adjustment of these eccentric washers will permit of the bolts being properly spaced laterally, even though the openings in the bowl be not 65 spaced to correspond therewith, or said

washers may be adjusted so as to cause the bolts to be properly positioned vertically should the openings be irregularly formed in the bowl, or be the means of varying the position of the seat, in any direction, with respect to the bowl. 70

By the use of my improvements the difficulties of properly positioning a seat upon a bowl are overcome and also the connecting parts are so constructed and arranged as to 75 give strength to the seat and retain the same in firm position.

While I have shown and described one particular embodiment of my invention, to a certain form of seat and bowl, I do not 80 wish to limit myself to the particular structure shown, as the same may be varied without departing from the spirit of my invention.

I claim as my invention and desire to secure by Letters Patent: 85

1. The combination of a closet bowl provided with bolt receiving openings, a seat, a hinge having one of the members thereof connected to the seat, and the opposite member adapted to be connected to the bowl, bolts engaging the said opposite hinge member and passing through the bolt receiving openings of the bowl, and means within each bolt opening for positioning the bolt 95 therein, said means being adapted by rotative adjustment to change the position of the bolt with respect to said opening.

2. The combination of a closet bowl provided with a bolt receiving opening, a seat, 100 a hinge having one of the members thereof connected to the seat, and the opposite member adapted to be connected to the bowl, a bolt engaging said opposite hinge member and passing through the bolt receiving 105 opening, and an eccentric washer member seated in the bolt receiving opening, the said eccentric washer member permitting lateral adjustment of the bolt within the opening.

3. The combination of a closet bowl provided with a bolt receiving opening having a recess at each end thereof, a seat, a hinge having one of the members thereof connected to the seat, and the opposite member adapted to be connected to the bowl, a bolt 110 engaging the opposite hinge member and passing through the bolt receiving opening of the bowl, and eccentric washer members seated in the recesses at each end of the bolt opening, the said eccentric washer members permitting of lateral adjustment 115 of the bolt within the opening.

4. The combination of a closet bowl, a seat, a hinge having one of the members secured to the seat, the opposite hinge member being adapted to be secured to the bowl and being formed with elongated openings, and a bolt formed with a laterally projecting head adapted to fit within each elongated opening of the hinge member to hold the 120

hinge member in position, the said laterally projecting head of the bolt being adapted to be reversed by turning the bolt so as to permit of adjustment of the hinge member upon the bowl.

5. The combination of a closet bowl provided with a bolt receiving opening, a seat, a hinge having one of the members thereof secured to the seat, the opposite hinge member being adapted to be secured to the bowl, and being formed with elongated openings, a bolt passing through each bolt receiving opening of the bowl and formed with a laterally projecting head adapted to engage 15 the elongated opening of said opposite hinge member to secure the same in position and also adapted to be reversed within the elongated opening of and to permit of adjustment of the hinge member upon the bowl, 20 and means within each bolt receiving opening of the bowl for holding the bolt in position when tightened and permitting lateral adjustment of the bolt within the opening when loosened.
25. 6. The combination of a closet bowl provided with a bolt receiving opening, a seat, a hinge having one of the members thereof secured to the seat and the opposite member thereof is adapted to be secured to the 30 bowl and formed with elongated openings, a bolt passing through each bolt receiving opening of the bowl and formed with a laterally projecting head adapted to engage in the opening of the said opposite hinge 35 member to hold the same in position and adapted to be reversed to permit of adjustment of the hinge member upon the bowl, and eccentric washer members seated in the opposite ends of the bolt receiving opening 40 so as to permit of lateral adjustment of the bolt within the opening.
7. The combination of a closet bowl provided with a pair of bolt receiving openings, a seat, a hinged connection between the seat

and the bowl including a seat connecting member and a pair of connecting members adapted to engage upon the bowl and formed with elongated openings, bolts passing through the bolt receiving openings of the bowl and formed with laterally projecting heads adapted to fit within the elongated openings of the bowl hinge members to hold the hinge members in position and adapted to be reversed within the elongated openings to permit of adjustment of the hinge members upon the bowl, and eccentric members seated in recesses formed at opposite ends of the bolt receiving openings and through which said bolts pass so as to permit of lateral adjustment of the bolts within 60 the bolt receiving openings.

8. The combination of a closet bowl, a seat, a hinged connection comprising a transversely disposed pivotal member applied to the rear of the seat and provided with a shoulder adjacent its pivotal portions, a pair of standards adapted to be secured to the bowl and to which said member is pivotally connected, said standards being each provided upon one face thereof with a 70 projection adapted to be engaged by the shoulders of the pivotal members to limit the backward swing of the seat.

9. The combination with a water closet bowl provided with bolt openings at the 75 rear for the seat connection, of a bolt in each opening, and means in each bolt opening and through which the bolt passes for positioning the bolt therein and adjusting the position of said bolt concentrically 80 thereabout.

In testimony whereof, I have hereunto signed by name in the presence of two subscribing witnesses.
